UNITED STATES PATENT OFFICE.

WILLIAM M. BOENNING, OF MANITOWOC, WISCONSIN.

YARN-WAXING MECHANISM.

1,099,534.

Specification of Letters Patent.

Patented June 9, 1914.

Application filed October 13, 1913. Serial No. 794,789.

To all whom it may concern:

Be it known that I, WILLIAM M. BOENNING, a citizen of the United States, and resident of Manitowoc, in the county of Manitowoc and State of Wisconsin, have invented certain new and useful Improvements in Yarn-Waxing Mechanism; and I do hereby declare that the following is a full, clear, and exact description thereof.

10 My invention consists in what is herein particularly set forth with reference to the accompanying drawings and pointed out in the claims of this specification, its object being to provide simple, economical means 15 in connection with yarn-winding apparatus for automatic application of wax to the yarn in mass upon a cop or spool, whereby breaking strain on said yarn winding from a skein is avoided, provision being had for 20 elevating and supporting the wax-holder elements of the means aforesaid out of working position.

Figure 1 of the drawings represents a plan view of a waxing-mechanism in accordance 25 with my invention positioned to have the wax-blocks thereof over a cone of yarn wound upon a suitably supported cop; Fig. 2, a partly sectional view indicated by line 2—2 in Fig. 1; Fig. 3, a front elevation of 30 a detail of the waxing-mechanism illustrating the shanks of the wax-block holders thereof swung up out of the way, and Fig. 4, a sectional view of a detail of said mechanism indicated by line 4—4 in Fig. 2.

35 Referring by numerals to the drawings, 5 indicates a stationary horizontal shaft-member of a yarn-winding apparatus such as is common in knit-goods factories, 6 a cop-holder arm loose on the shaft, 7 a cop in connection with the arm, and 8 a cone of yarn wound on the cop from a skein. Fast on the shaft 5 is a sleeve 9 having a partly covered outer annular groove 10 oblique to its axis. The sleeve shown is separable, and the sections thereof are clamped on the shaft 5 by means of suitably disposed screws 11, the groove in one section of said sleeve being partly covered by a plate 12 held in place by screws. Engaging the sleeve within the

50 groove of the same is shown a pair of outwardly round hook-plates 14, 15, each having a laterally extending angle-arm. The arm 14' of the hook-plate 14 extends in an opposite direction to that of the arm 15' of the hook-plate 15, and rigidly secured in connection with said arms are stems 16, 17,

respectively, one of the stems being straight and the other partly offset as shown in Fig. 1. As a matter of detail, the inner ends of the stems are screw-threaded in the arms of the hook-plates and nuts 18 opposing said arms. Arranged on each of the stems is a pair of right-angle clamp-plates 19, 20. The inner one of these plates is provided with a boss 19' in opposition to a nut 21 for which the stem is screw-threaded, and the outer one of said plates is provided with a boss 20' fastened to said stem by a key-pin 22. The hook-plates, stems, clamp-plates and nuts combine to form carriers having pivotal play connection with the sleeve, and caught between each pair of the clamp-plates is a block 23 of suitable wax, such as paraffin, tension on the same being had by tightening the set-nut 21 against the opposing clamp-plate boss, said block of wax being notched to clear the stem upon which said clamp-plates and nut are arranged.

A spring-controlled latch-bolt 24 is guided in the arm 14' of the hook-plate 14, and another arm 25 fast on the stem 16, the spring 26 being arranged on the bolt between a collar 24' of the same and the stem-arm. The stem 16 and clamped block of wax therewith being swung up, the latch bolt 24 80 engages back of a lug 9' of the aforesaid sleeve in its path to hold said block of wax out of working position and the upward play of the stem 16 is limited by the sleeve-groove cover 12, that also serves to prevent an automatic disengagement of the aforesaid hook-plates from said sleeve-groove.

90 A lateral lug 27 of the hook-plate 14 extends back of the angle-arm 15' of the hook-plate 15, and the stem 16 being swung up, the stem 17 is carried along to elevate the block of wax therewith out of working position where it is held as a result of the automatic latching operation of the bolt 24 above described.

To facilitate holding of the wax-block between a pair of clamp-plates, each of said plates is provided with suitably arranged inner gripping studs 28 shown in Figs. 1 and 4.

105 In practice the blocks of wax are positioned to have gravity opposition to a cone of yarn winding on a cop from a skein, and the construction and normal arrangement of parts above specified is such that the wax-blocks automatically accommodate themselves to the increasing thickness of said

cone. Owing to the above specified disposition of the groove in the stationary sleeve, the blocks of wax are constantly parallel to the cone of yarn in their working position, but for waxing the wound yarn in straight spools, said groove would be parallel to the ends of said sleeve without departure from my invention as herein claimed.

I claim:

- 10 1. The combination in a yarn-winding apparatus of a horizontal support, carriers pivotally adjustable on the support, a block of wax in connection with each carrier to have gravity opposition to a winding cone 15 of yarn, and latch-mechanism by which to hold said carriers stationary in elevated position.
- 20 2. The combination of a sleeve for rigid connection with a stationary shaft of a yarn-winding apparatus and having an outer annular groove oblique to its axis, carriers having ends thereof in pivotal play connection with the sleeve within the groove thereof, and blocks of wax in connection with the 25 carriers for opposition to a winding cone of yarn.
- 30 3. The combination of a separable sleeve for rigid connection with a stationary shaft of a yarn-winding apparatus and having an outer annular groove oblique to its axis, carriers having ends thereof in pivotal play connection with the sleeve within the groove thereof, and blocks of wax in connection with the carriers for opposition to a winding 35 cone of yarn.
- 40 4. The combination of a sleeve for rigid connection with a stationary shaft of a yarn-winding apparatus and having a partly covered outer annular groove, carriers having outwardly rounded hook-plate ends engageable with the sleeve within the groove thereof, and blocks of wax in connection with the carriers for opposition to a winding cone or spool of yarn.
- 45 5. The combination of a sleeve for rigid connection with a stationary shaft of a yarn-winding apparatus and having an outer annular groove, a pair of carriers in pivotal play connection with the sleeve, blocks of

wax in connection with the carriers for opposition to a winding cone or spool of yarn, a lifting-lug extending from one carrier under the other, and means for latching said carriers out of working position.

6. The combination of a sleeve for rigid connection with a stationary shaft of a yarn-winding apparatus and having a partly covered outer annular groove, a pair of hook-plates engaging the sleeve within the groove thereof and having oppositely extending lateral arms, screw-threaded stems in connection with the arms and one of the same suitably offset, a fixed and movable clamp-plate on each stem, a nut on each stem in opposition to the movable clamp-plate therewith, a block of wax caught between each pair of clamp-plates, a lug extending from one hook-plate under the arm of the other hook-plate, and means for latching said hook-plates and parts therewith out of working position.

7. The combination of a sleeve for rigid connection with a stationary shaft of a yarn-winding apparatus and having a partly covered outer annular groove, a pair of hook-plates engaging the sleeve within the groove thereof and having oppositely extending lateral arms, screw-threaded stems in connection with the arms and one of the same suitably offset, a fixed and movable clamp-plate on each stem, a nut on each stem in opposition to the movable clamp-plate thereon, a block of wax caught between each pair of clamp-plates, a spring-controlled latch-bolt guided in connection with one of the stems, a latch-keeper lug on said sleeve, and means by which a lift of the bolt-carrying stem into latched position results in an elevation of the other stem.

In testimony that I claim the foregoing I 90 have hereunto set my hand at Manitowoc, in the county of Manitowoc and State of Wisconsin, in the presence of two witnesses.

WM. M. BOENNING.
